TRIM PANEL

Paul R. Zinser, Detroit, Mich., assignor to Woodall
Industries Incorporated, Detroit, Mich., a cor-
poration of Michigan

Application April 20, 1936, Serial No. 75,321

6 Claims. (Cl. 154—2)

This invention relates to improvements in fabricated trim panels and improvements in the method of fabricating such panels.

An object is to provide a trim panel, particularly designed for the interior of an automobile body, which presents the appearance of an expensive upholstered padded trim panel at low cost and without stitching.

Another object is to provide a padded trim panel of superior quality which presents an upholstered tufted appearance without actually tufting or stitching the same. The panel is characterized in that it may be fabricated of inexpensive materials at low cost and it is of durable and moisture resistant construction.

Another object is to provide an improved method of fabricating a padded trim panel without stitching or tufting and at low cost and so as to present any desired design of tufting or the like.

This improved panel comprises a panel foundation, such as fiber board, a soft layer of wadding overlying the board and an outer covering of trim material. The several layers are adhesively secured together and the tufted design is obtained by adhesive saturation of the wadding along determined lines of compression and adhesive securement of the wadding in its compressed state to the board along such lines. Along such lines the trim material is likewise adhesively fastened down.

The wadding throughout its uncompressed areas is fluffy, resilient and unsaturated with adhesive though normally highly absorbent. The uncompressed areas of the wadding are protected against moisture absorption by a surrounding moisture resistant barrier. This barrier comprises a moisture resistant sheet overlying the wadding, a moisture resistant supporting panel and moisture resistant adhesive saturated densified lines of compression of the wadding itself connecting the overlying barrier sheet to the supporting panel. Such barrier sheet likewise protects the layers underneath the trim fabric from the action of cleaning solutions used on the fabric as the barrier is resistant to the attack of such cleaning compounds. This barrier further is important as certain panel foundation boards carry a binder which is soluble in cleaning compounds and the overlying barrier protects the foundation board against the attack of such cleaning compounds, which are widely used.

An important characteristic of the improved method comprises the adhesive saturation of the wadding along lines of compression by absorp-

tion of adhesive from the adhesive coated surface of the panel board through compression of the wadding along such lines against the board. The method is further characterized in that the uncompressed areas of wadding do not absorb adhesive but remain loose, fluffy and resilient. Compression of the absorbent wadding against the adhesive coated surface of the foundation along determined lines so saturates the wadding along such lines of compression as to produce permanent adhesive densification of the wadding therealong and fastens the trim cloth along such lines securely to the board producing the desired padded configuration.

An important feature is the employment of an adhesive such as a latex compound which is applied to the foundation board and to the trim material and which upon compression of the intermediate wadding layer securely fastens the trim material to the board along such compressed line.

Another important feature is the provision of a latex saturated barrier sheet overlying the wadding and forming a backing sheet for the trim cloth which barrier sheet readily adhesively picks up and retains its connection with the latex absorbed by the wadding along the line of compression.

A further meritorious feature is that this latex saturated backing sheet may preferably comprise a latex saturated tissue thin outer cover sheet of the wadding itself which forms an adhesive connection with the latex coated inner surface of the trim cloth and with the latex saturated compressed portion of the wadding.

In the method a preferred step is to compress the wadding and adhesively secure the same in the compacted state along relatively wide lines of compression. The trim cloth is then adhesively secured to the wadding along such compacted line but compressed thereagainst along a line relatively less wide than the compacted line of wadding.

Other objects, advantages and meritorious features of this invention will more fully appear from the following description, appended claims and accompanying drawing, wherein:

Figure 1 is an elevation of a trim panel embodying my invention,

Fig. 2 is a cross-sectional view taken on the line 2—2 of Fig. 1,

Fig. 3 is an enlarged cross-sectional view of a fragment of a panel embodying my invention,

Fig. 5 is an enlarged cross-sectional view of a panel on the line 5—5 of Fig. 1 but illustrating the appearance after compression of the wadding but prior to the securement of the trim cloth.

In Fig. 1 I have shown a panel presenting a padded design but it is to be understood that any desired type of design may go with the panel as the method here set forth is adaptable to embossed designs of any shape.

In the fabrication of a panel embodying my invention there is provided a foundation board such as is indicated at 10. This may be any suitable type of composition fiber board. It is desirable that such board be moisture resistant in order to prevent warping, buckling and the like, and a board which I have found satisfactory is a board formed of cellulose fibers held together by a suitable binder such as an asphaltum composition binder. Such a board is well-known on the market under the name of K B board. It may be stamped or otherwise shaped as it possesses thermoplastic characteristics which permits it to respond to heat and pressure to assume and permanently retain a deformed shape. It is of course understood that such a type of board is not essential as the embossed appearance is given to the design by the embossment of the wadding as hereinafter described.

A layer of wadding is provided to overlie the surface of the board. It is desirable to have a soft, fluffy, resilient, inexpensive wadding, and a wadding which has been found satisfactory is one formed of loosely integrated cellulose fibers. As here shown, such wadding is indicated as 12 and is made up of a plurality of filmy, cobweb-like plies of cellulose fibers. Such number of plies are provided as is desired for the thickness of wadding needed. Preferably this wadding is fabricated with a backing or cover sheet 14 shown enlarged in Fig. 3 but which has been found suitable in the form of a thin tissue-like sheet of paper saturated with latex so as to strengthen it and render it moisture resistant. This cover sheet forms a support and protection for the loose wadding and facilitates its handling. It likewise forms a cover therefor to prevent ingress of moisture from the trim side. The cover sheet also serves other important functions.

The panel is trimmed with upholstery trim material. This may be a fabric sheet such as indicated at 16 or 26, or it may be a sheet of artificial leather or any other desired flexible trim sheet. This upholstery fabric forms the outer cover of the panel structure and in the completed panel may be folded over the edge onto the back thereof as indicated at 18 and adhesively secured to the back of the panel to provide a finished panel and to protect the edge of the wadding and to hold the same down at the margin of the panel.

In the fabrication of the panel one surface of the panel foundation board is covered with a generous coating of a suitable adhesive such as latex compound indicated in exaggerated thickness as a layer 20 in Figs. 3 and 5. One surface of the trim material 16 is likewise sprayed with an adhesive compound of a similar character indicated as at 22 in Fig. 3. The wadding layer 12 with the protective sheet 14 is placed upon the adhesive coated surface of the foundation board. The adhesive coating 20 on the foundation board secures the wadding layer 12 thereto.

The panel and wadding is then placed in a suitable die and subjected to a die stamping operation to impart the desired embossed design

thereto. The die is so fashioned that it compresses the wadding against the foundation board only along the lines of desired debossment. The die is recessed between these projecting portions so that the wadding is not compacted throughout the areas between the lines of compression. In Fig. 5 the wadding is shown compressed against the foundation board at 24. Between the lines 24 the wadding is not compressed. Along these lines of compression the wadding absorbs sufficient adhesive throughout its compressed area from the adhesive coat on the foundation board to thoroughly saturate the wadding. Along the line of compression the wadding assumes and permanently retains its compressed state due to this compacted adhesive securement of the fibers thereof together. The latex securely bonds the fibers of the wadding together and engages the latex saturated sheet 14 forming a secure connection therewith. This line of compression is relatively wide. The wadding is densified along such line forming a sealed line around each uncompacted area.

The adhesive coating 20 on the foundation board is supplied in such thickness that upon compression of the layer of wadding thereagainst there is sufficient adhesive to penetrate through the compressed thickness of wadding but there is not sufficient adhesive to soak through the wadding over its uncompressed areas. Throughout the areas which are not compressed the adhesive merely secures the wadding adhesively to the board but does not substantially penetrate or soak therethrough.

The trim fabric 26, coated on its under side with similar latex adhesive is now placed over the wadding. The complete panel is then placed in a die of the same general contour as used to compress the wadding but constructed to produce lines of compression of substantially less width as illustrated in Fig. 2 and provided with cooperating force and die members adapted to give a fine shape to the wadding and to impart the embossed design to the foundation board as shown in Fig. 2. The slope of the trim fabric is relatively gentle from the depth of the compressed line outwardly toward both sides. There is not the sharp rise that would be the case if the wide line were not first established in the wadding. The wide line of compression in the wadding also provides a secondary connection with the board.

If a particularly heavy and thick wadded area is desired, a piece of wadding 27 may be cut to size and placed upon the layer of wadding 12 and the line 24 of compression conforms so as to encircle this cut piece of wadding. This might be necessary if the layer of wadding 12 plus the layer 27 would be too thick to absorb throughout its entire thickness the required quantity of adhesive to form the bond along the line of compression.

In Fig. 4 I have shown a depressed line wherein the die force is so formed as to provide imitation stitching indicated by depressions 28 formed in the bottom of the groove 24 as is set forth in my Patent No. 2,019,641. The particular invention herein described lends itself to such type of die stamping in that it readily responds to the formation of these artificial stitch depressions.

If the foundation board is adaptable for stamping it may absorb part of the embossment as shown in Fig. 2 where the board is deformed slightly below the groove 24 and the wadding.

The wadding which I provide is relatively highly absorbent and the adhesive quickly soaks through the compacted lines or portions thereof

to form the seal and connection which holds the trim fabric down along such compressed lines. The latex adhesive forms a moisture resistant barrier which protects the wadding layer 5 12 against absorbing moisture. If the foundation layer is formed of moisture resistant board as above described it also serves to accomplish the same end. The latex saturated tissue sheet 10 14 is likewise moisture resistant and the compacted lines 24 throughout which the latex has formed a secure connection serves to provide pressed areas of the wadding and protecting the same against moisture.

Due to the fact that the cover sheet 14 is 15 latex saturated it quickly picks up the latex soaking through the compressed line of wadding and forms a secure connection therewith and holds the wadding to the desired embossed design and likewise holds the trim fabric to the foundation board. The uncompressed areas of wadding are 20 practically hermetically sealed.

The barrier sheet 14 not only protects the wadding against moisture but prevents cleaning materials which may be used to clean the upholstery 25 fabric from soaking into the wadding and also from acting upon the foundation board 10. Certain widely used cleaning materials are of such a character as will dissolve the binder in the foundation board. The binder then flows to 30 the surface and discolors the trim fabric. The cover sheet 14 being resistant to the attack of these cleaning fluids prevents them from reaching the foundation board and likewise prevents the binder in the board from soaking through the 35 wadding to contaminate the upholstery cloth.

What I claim is:

1. A trim panel comprising a foundation board, a layer of wadding overlying the board, a layer of trim material overlying the wadding, said 40 wadding being saturated with adhesive and compressed against the foundation board along a relatively wide line surrounding an uncompressed area throughout which the wadding is adhesively secured to the board but is not compacted thereagainst, said trim material being compressed along a relatively narrow line against the relatively wide compressed line of wadding and secured adhesively thereto.

2. That method of fabricating a trim panel 50 comprising placing a layer of wadding over a foundation board, compacting and adhesively securing the same compacted thereagainst along a predetermined line of substantial width, placing a sheet of trim material over said wadding and 55 compacting the same against the compacted line of wadding along a line of relatively less width than said compacted line of wadding adhesively securing the trim sheet thereto.

3. A trim panel comprising a foundation layer 60 having one surface provided with an adhesive coating, a layer of adhesive absorbent wadding overlying the surface of the foundation layer provided with the adhesive coating, a layer of trim material overlying the wadding, said wadding being compressed against the foundation layer along a line defining an uncompressed area of wadding and saturated throughout along said 65 line with adhesive absorbed from the foundation layer and adhesively secured compressed together and to the foundation layer along said line by said absorbed adhesive, said trim material being adhesively secured to the foundation layer along said line of compression of the wad-

ding through said compressed line of adhesive saturated wadding said wadding throughout its uncompressed area being unsaturated with said adhesive.

4. A trim panel comprising a foundation layer 5 having one surface provided with an adhesive coating, a layer of adhesive absorbent wadding overlying the surface of the foundation layer provided with the adhesive coating, a layer of trim material overlying the wadding, said wadding being compressed against the foundation layer along a line defining an uncompressed area of wadding and saturated along said line with adhesive absorbed from the foundation layer and adhesively secured compressed together and to 10 the foundation layer along said line by said absorbed adhesive, said trim material being adhesively secured to the foundation layer along said line of compression of the wadding through said compressed line of adhesive saturated wadding, and a second layer of wadding underneath the trim layer overlying the first layer of wadding throughout the uncompressed area thereof only, and spaced within the saturated compressed line of the first layer of wadding and 15 positioned upon said first layer of wadding by the adhesion of the trim material to the first layer along said saturated line of compression both layers of wadding throughout the uncompressed area being unsaturated with said adhesive.

5. That method of fabricating a laminated trim panel structure comprising providing a foundation layer with a coating of adhesive, placing a layer of absorbent wadding upon said coated surface of the foundation layer but without compression thereagainst adhering the wadding thereto but without saturating the same throughout, said wadding being sufficiently absorbent of said adhesive and said adhesive being 40 present in sufficient amount that upon compression of the wadding into a densified line against the foundation layer the wadding along said line absorbs adhesive from the foundation layer saturating the wadding throughout along said 45 line, compressing said wadding along a line defining an uncompressed area of wadding against the adhesive coated surface of the foundation layer, densifying the wadding along said line and causing it to absorb adhesive throughout along said line adhesively securing the wadding compacted together and to the foundation layer along said line.

6. A laminated trim panel comprising a foundation layer provided upon one surface with 55 a coating of adhesive, a layer of absorbent uncompressed wadding of substantially greater thickness than the foundation layer overlying the adhesive coated surface of the foundation layer and secured thereto by said adhesive coating but 60 without saturation throughout the uncompressed area thereby, a moisture resistant cover sheet overlying the wadding, a layer of trim material overlying the cover sheet, said wadding being compacted against the foundation layer along 65 a line outlining an uncompressed area and compacted sufficiently so that the adhesive coating on the foundation layer saturates the wadding throughout along the line of compression securing the wadding adhesively compressed together along said line and against said foundation layer. 70
